ALARM TIME-PIECE

Georges Olivier Bridevaux, 36 Rue Pierre Pertuis,
Tavannes, Switzerland
Filed Dec. 6, 1966, Ser. No. 599,476
1 Claim. (Cl. 58—16)

ABSTRACT OF THE DISCLOSURE

Alarm time-piece including a movement barrel and an alarm barrel associated with a single winding mechanism for both barrels, in which the two barrels occupying in plan view one half of the surface of the clock and the thickness of the clock while the part actuating the winding mechanism is located at the periphery of the clock the alarm movement and the clockwork movement being superimposed in the other half of the movement in substantially the same plane, the part actuating the winding mechanism being located at the periphery of the movement and at least approximately in diametrically opposite relationship with reference to the part adjusting the time at which the alarm is to be released.

This application is a continuation in part of my previous application Ser. No. 405,080, now abandoned filed Oct. 20, 1964.

The accompanying drawings illustrate by way of example a preferred embodiment of the present invention.

In said drawings: FIGURE 1 is a view of the back of the time-piece; FIGURE 2 is an inner view of the different parts thereof; FIGURE 3 is divided into two sections forming together a cross-section through line III—III of FIGURE 2; FIGURE 4 is a view cut away of the back of the time-piece; and FIGURE 5 is a cross-sectional view taken along line V—V of FIGURE 4.

The embodiment illustrated includes a casing 1 carried by a pedestal 2 and provided with a bottom 3 secured to the frame of the movement by three screws 4. The spindle carrying the minute hand extends through the center of the bottom, and carries the knob 5 and the spindle driving the gear adjusting the time of alarm and rigid with a knob 6 passes eccentrically through said bottom and a winding key 7 which allows winding in succession the movement spring and the alarm spring is also carried by the bottom 3.

Said bottom is also provided with a lever 8 adapted to stop the ringing of the alarm and with a gate 9 through which it is possible to modify the adjustment of the movement. The winding key 7 and the knob 6 adjusting the time of release, are located in the vicinity of the periphery of the casing so that the distance between the central time-setting knob 5 and each of said parts 6 and 7 may be as great as possible.

This condition is satisfied by the special arrangement of the different members forming the movement and the alarm mechanism as illustrated diagrammatically in FIGURE 2 and cross-sectionally along line III—III of FIGURE 2 in FIGURE 3. The plates 25 and 26 are assembled by pillars 27 engaged by screws 28. The winding shaft 44 rigid with the key 7, is revolvably carried in the plate 26. The wheel 11, rigid with said shaft meshes with the transmission gear 12 fitted on the yoke 13. The latter provides for the drive according to the angular shifting to which it

2

is subjected, of ratchet wheel 14 fitted over the square end of the movement barrel spindle 29 or of ratchet wheel 15 rigid with the alarm barrel spindle 30 of substantially the same height as 29. The movement barrel 10 drives, through the intermediate gear 31, the center wheel 32 on the square spindle 16 of which is fitted the time-setting knob 6. The clockwork gear of a conventional structure, includes the third wheel 33, the fourth wheel 34, the escape wheel 35, the anchor 36 and the balance wheel 17 riveted on its staff 37. These five moving members are pivotally carried by an intermediate plate 38 and holding the lower extremity of the clockwork superimposed over the alarm mechanism of which the hammer is shown at 20 and the alarm power wheel at 39. The cross-sectional FIGURE 3 shows also the dial 40, the hands 41 and the glass 42. The alarm barrel 9 drives, through the wheel 43, the alarm wheel 39 cooperating with the hammer 20, as will be indicated later.

The plan view of FIGURE 2 shows that the two barrels occupy one half of the plane of the movement while the cross-section of FIGURE 3 shows in addition to the considerable height provided for the barrels, the superimposition of the time mechanism 21 over the alarm mechanism, which allows locating at the periphery of the casing, the operative parts 6 and 7 which are arranged at least approximately at the opposite ends of a diameter and as far as possible from each other, these two mechanisms both lying in the plane occupied by said barrels.

The invention is not limited to the embodiment described hereinabove and it covers also other embodiments wherein the casing may be given a polygonal shape in which case the operative parts 6 and 7 are positioned at least approximately at the opposite ends of one of the diagonals of said casing.

FIGURE 5 shows how intermediate plate 44 holds the upper ends of the mobiles of the alarm movement and on plate 44 is placed plate 38 which supports the timepiece movement thus forming two levels between plates 25 and 26. Shaft 46 is the control shaft for adjusting the alarm and is integral with wheel 47 which has an opening (not shown). Wheel 47, manually set by button 6, is operatively associated to an alarm hand in the center of the movement and rigid with the tube of wheel 48. The alarm is set off by intermediate wheel 50 (coaxial with the other intermediate wheel 49 linking 47 and 48) but independent therefrom. Hour wheel 51 meshes with wheel 52 through intermediate wheel 50. Wheel 52 is freely pivoted on shaft 46 and has a cam 53 cooperating with the opening of the shoulder of wheel 47 in usual fashion. Spring 54 causes wheels 52 and 47 to bear axially one against the other so that when the opening of 47 passes in front of cam 53, the cam will enter it and thus free the end of hammer 20 causing ringing.

FIGURE 4 shows means for stopping the alarm which consist of lever 56 which has a stud 58 which fits under lever 54 and puts it in the position shown in FIGURE 5 under hammer 20 to prevent it from vibrating by pushing on button 55.

The alarm time-piece according to the invention, ensures thus a spacing as large as possible between the winding and time-setting parts which prevents the user from fortuitously moving one of said parts when he actuates an adjacent part and thereby the safety of operation is considerably increased.

What is claimed is:

In an alarm time-piece, the combination of a casing, an alarm barrel and a clockwork barrel mounted together in one diametrical half of the casing, a common winding part for both barrels positioned near the periphery of the casing, a clockwork movement controlled by the clockwork barrel, an alarm mechanism controlled by the alarm barrel, said movement and said mechanism being superimposed with respect to one another in the other half of the casing, a time setting part cooperating with the movement and lying at the center of the casing and a part adjusting the time of release of the alarm mechanism and positioned near the periphery of the casing in substantial opposed diametrical relationship with reference to the common winding part.
